Primary Examiner — Kelley Donnelly(74) *Attorney, Agent, or Firm* — Pearne & Gordon LLP**CLAIM**

The ornamental design for a basket, as shown and described.

DESCRIPTION

FIG. 1 is a perspective view of an example basket;
 FIG. 2 is a right side plan view thereof, the left side plan view
 being a mirror image thereof;
 FIG. 3 is an end view thereof;
 FIG. 4 is a front view thereof;
 FIG. 5 is a top view thereof; and,
 FIG. 6 is a bottom view thereof.
 The broken line showings of FIGS. 1-6 are for illustrative
 purposes only and form no part of the claimed design.
 The broken lines that define the bounds of the claimed design
 form no part thereof.

1 Claim, 5 Drawing Sheets**US D688,870 S**
